(57) **CLAIM**

The ornamental design for an adjustable table, as shown and described.

DESCRIPTION

FIG. 1 is a top perspective view of an adjustable table showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-section view thereof, taken along line 9-9 in FIG. 1;

FIG. 10 is a cross-section view thereof, taken along line 10-10 in FIG. 1; and,

FIG. 11 is a partially enlarged perspective view thereof at the location surrounded by the dot-dash broken lines 11 of FIG. 2.

The broken lines in the figures form no part of the claimed design.

The dot-dash broken line markers in FIG. 2 delineate portions of the adjustable table that are shown enlarged in FIG. 11. The dot-dash broken lines form no part of the claim.
